United States Patent Office.

L. AUSTIN AND JOSHUA E. HALL, OF CLEVELAND, OHIO.

Letters Patent No. 99,280, dated February 1, 1870.

IMPROVEMENT IN POWDER-KEG.

The Schedule referred to in these Letters Patent and making part of the same.

To all whom it may concern:

Be it known that we, L. AUSTIN and JOSHUA E. HALL, of Cleveland, in the county of Cuyahoga, and State of Ohio, have invented certain Improvements in Powder-Kegs; and we do hereby declare that the following is a full, clear, and complete description of the same, reference being had to the accompanying drawings, making part of this specification, in which drawings—

Figure 1 is a perspective view of a powder-keg.

Figures 2, 3, and 4, detached transverse sections, to which reference will be made.

Like letters of reference refer to like parts in the several views.

Objective.

The object of this invention is to produce a safe, strong, and cheap keg, consisting of a compound of metal and wood, for the reception and transportation of gunpowder, as hereinafter more fully described.

Descriptive.

In fig. 1—

A represents the side or body of the keg, and which is constructed of sheet-metal.

B, the bottom, is attached thereto by any of the usual locks or seams adopted by the manufacturers of tin-ware.

Around the upper part of the keg, near to the top, is impressed a groove, C, forming thereby, on the inside of the keg, a shoulder, D, fig. 4.

Upon said shoulder, and closely fitting the inside of the keg, above the same, is inserted a wooden top or head, E, having an aperture or stopper-hole, F.

Superimposed upon said head is a metal plate or auxiliary head, G, fitting closely the inside of the keg, as does the wooden head, also provided with a stopper-hole, the edge of which is bent downward, forming a partial lining to the hole in the head E.

The two heads G E, as thus placed in relation to each other, are secured therat by turning over and lapping down upon the metal head, the edge of the

side of the keg, as shown at C. By this means, the two heads are firmly and securely attached to each other, and to the sides of the keg, thereby making a tight, safe, and durable top to the same, and providing a depth to the hole that will embrace the stopper in a permanent and reliable manner.

It will be obvious that in a keg as thus constructed, the head thereof cannot be easily forced in, per consequence of the shoulder D, on which it is made to rest. Also, neither can it be forced therefrom, per consequence of the lapping down thereon of the edge of the keg; hence, a safe, light, and durable keg is provided for the holding and transportation of powder.

Fig. 2 shows a slight modification of fig. 4.

It will be observed that in this keg, the metallic or auxiliary head H is not fitted to the inside of the keg, but is made somewhat larger in diameter, so as to project over the sides upon the outward edge of the keg, which it embraces, forming a double lock-seam, as shown at I, fig. 2, which represents a transverse section of the head and sides of the keg.

It will be seen that said head is so constructed that its edge is turned down, forming a deep annular flange, K, the lower edge of which rests upon the shoulder D, which prevents it from being pressed inwardly, and which is prevented from being forced outwardly by the turning down and lapping upon the head, the edge of the keg, as shown at C.

Claim.

What we claim as our invention, and desire to secure by Letters Patent, is—

The body A, with shoulders D D, in combination with wooden head E and auxiliary head H, in the manner as described, and for the purpose set forth.

L. AUSTIN.

J. E. HALL.
